(Cl. D31—2)

To all whom it may concern:

Be it known that we, Bernard B. Verosub and Louis Lipman, citizens of the United States of America and residents of Newark, county of Essex, and State of New Jersey, and Hillside, county of Union, and State of New Jersey, respectively, have invented a new, original, and ornamental Design for a Bird Cage Ornament, of which the following is a specification, reference being had to the accompanying drawings, forming a part thereof.

Figure 1 is a front elevational view of a bird cage ornament, showing our new design;

Figure 2 is a side elevational view thereof;

Figure 3 is a rear elevational view;

Figure 4 is a top plan view.

We claim:

The ornamental design for a bird cage ornament, as shown.

BERNARD B. VEROSUB.
LOUIS LIPMAN.
